UNITED STATES PATENT OFFICE.

JOHN L. BUCKINGHAM AND JOHN F. YEATES, OF HERMOSA, SOUTH DAKOTA.

SNAP-HOOK.

SPECIFICATION forming part of Letters Patent No. 449,870, dated April 7, 1891.

Application filed September 15, 1890. Serial No. 365,068. (No model.)

To all whom it may concern:

- Be it known that we, JOHN L. BUCKINGHAM and JOHN F. YEATES, citizens of the United States, residing at Hermosa, in the county of 5 Custer, State of South Dakota, have invented certain new and useful Improvements in Snap-Hooks, of which the following is a specification, reference being had therein to the accompanying drawings.
- 10 This invention relates to certain new and useful improvements in snap-hooks for harnesses; and it has for its object, among others, to provide a simple, cheap, and durable device of this character.
- 15 The novelty resides in the peculiarities of construction of the snap-hook, as more fully hereinafter described, shown in the drawings, and then particularly pointed out in the appended claim.
- 20 The invention is clearly illustrated in the accompanying drawings, which, with the letters of reference marked thereon, form a part of this specification, and in which—
Figure 1 is a side view of the snap-hook with portions broken away. Fig. 2 is an edge view of Fig. 1. Fig. 3 is a perspective view of the spring-bolt detached.
- 25 Like letters of reference indicate like parts throughout the several views.
- 30 Referring now to the details of the drawings by letter, A designates the body portion of the snap-hook, formed with ears a, through which is passed the bolt or rod B to receive the end of the trace in the usual manner.
- 35 C is a spring-bolt arranged to connect with the whiffletree. The snap-hook is arranged to open and close by means of said spring-bolt, which is formed of a body portion to complete the contour of the hook of the snap-hook, as shown in Figs. 1 and 2, having its outer end beveled or formed on an incline, as shown in Fig. 1, to conform to the tapered end of the hook portion of the snap-hook. The bolt is formed with a reduced spring-45 shank c, which is tapered to a point and is forced into a socket c' in the body of the snap-

hook, as seen best in Fig. 1, said socket at its outer end being enlarged into the space enclosed by the ring portion of the snap-hook, as seen best in Fig. 1, so as to allow free movement of the spring-bolt, as indicated by dotted lines in Fig. 1. The spring portion c of the bolt extends from one side of the circular portion thereof, leaving a square shoulder e, which bears against the end of the body portion in which the socket is formed, as shown in Fig. 1, so as to relieve the spring portion of the spring in case pressure is brought to bear against the body portion of the bolt, which completes the contour of the ring or hook portion of the snap-hook.

In practice the body portion of the bolt will give or yield sufficient to allow of the passage of the whiffletree-ring, as indicated by dotted lines in Fig. 1, but automatically return to its 65 normal position after the ring has passed. It forms a safety snap hook, as the whiffletree-ring cannot accidentally become detached either while going downhill or on the slackening of the traces. The bevel of the outer end 70 of the body portion of the bolt, together with the outer shoulder e, serves to prevent breakage of the bolt by sudden strain thereon.

The body portion of the bolt is provided with a thumb-piece or projection f, which is 75 located upon the inner side of the spring-bolt, thus rendering it much less liable to come in contact with any obstructions which might disconnect the spring-bolt.

The device is simple, inexpensive, and in 80 practice has proved most efficient.

It is deemed important that the bolt C and its tongue be formed of a single piece of material, as it is more durable, cheaper, and less liable to get out of order. It is also deemed 85 important that the said tongue be tapered and springs and forced into a socket in the body portion of the snap-hook and there held by frictional contact of the parts, thus avoiding the necessity of the employment of screws 90 or other fastening means, as has heretofore been proposed.

What we claim as new is—

The snap-hook described, consisting of a body portion formed with the recess extending into the body of the body portion and having enlarged entrance, and the spring-bolt completing the contour of the eye and formed with the tapered spring portion *c*, beveled outer end, square shoulder *e* at the junction of the body portion and spring portion, and a thumb-piece upon the inner side of the body portion of the bolt, substantially as described.

In testimony whereof we affix our signatures in presence of two witnesses:

JOHN L. BUCKINGHAM.
JOHN F. YEATES.

Witnesses to signature of Buckingham:

MILTON R. MAXSON,
JOHN W. STRATER.

Witnesses to signature of Yeates:

A. ARNOLD,
B. GALLAND.
